HYDRANT

Noel M. Anderson, Des Moines, Iowa

Application August 30, 1950, Serial No. 182,261

7 Claims. (Cl. 137—304)

1

My invention relates to hydrants and is an improvement over the device disclosed in my co-pending application on a Yard Hydrant filed July 16, 1949, and having application Serial Number 105,160.

Hydrants are not new and have long been used in connection with large water systems. However, as electric power has now made it possible, especially for farmers, to pump water from their own wells under pressure, individual yard hydrants have become increasingly more commonplace.

The benefits of a water system to the farmer cannot be utilized unless he can deliver the water where it is needed, such as the watering trough or in his barn or the like. Thus, to have water available when and where he needs it, a yard hydrant is usually located at selected sites. Obviously, such sites are frequently in the open and therefore precautions must be taken to prevent ice from forming in the hydrant during cold weather and thereby rendering it inoperable. This is done by placing the lower valve portion in the ground below the frost line or by placing it in a covered pit adjacent the pump, and having only the upper nozzle part extending above the surface. Also, present type yard hydrants are provided with a drain hole in the valve seat body to carry off the water left in the standpipe after the valve is closed. This hole also serves as a place for water to drain out into the ground in the event of any leakage around the valve seat washer. This latter purpose is necessary for while valves are not supposed to leak they frequently do, and if the water from such a leak should rise in the standpipe above the frost line, it will freeze in cold weather.

However, most present type yard hydrants having the features above enumerated have several disadvantages, particularly for the farmer, which I will endeavor to point out.

Quite frequently a farmer will desire to turn his hydrant on for a continuous slow flow such as for a milk-cooling tank or keeping a watering trough at a desired level or the like, and when this is done, as it frequently is, the hydrant becomes in effect nothing more than a conduit. To do this, however, will often result in a considerable leakage and loss of water through the drain hole in the valve seat body. This is true because most present type hydrants are constructed so that the valve assembly on the valve stem running to the valve seat will close off the drain hole only when the valve is substantially fully opened. Consequently, if the valve is only partially open as is the case for a slow flow, the drain hole is either partially closed or not closed at all with the result that over an extended period of time a substantial amount of water passes out through the drain hole as well as out of the nozzle. This

2

is an important factor when water is pumped from a well because the more water lost through leakage, the more the pump will operate, and in case of a low water supply the unnecessary waste of water can become critical.

In some present type hydrants a sleeve of rubber or the like arranged on the valve assembly is designed to close off the drain hole when the valve is open and such a construction will function substantially satisfactorily when the hydrant is used intermittently, but when the hydrant is opened for a continuous flow, experience has shown that the continuous constant pressure against the sleeve eventually results in water finding its way into the drain hole where it is not only wasted, but unnecessarily saturates the ground adjacent the drain outlet which obviously adversely affects the efficiency of drainage at this point.

These objects I have overcome by my invention, the principal object of which is to provide an improved means for preventing the escape of water through the drain hole in a hydrant when the hydrant valve is in open position.

More particularly my invention has special utility when the hydrant valve is open for extended periods of time.

Specifically my invention embodies the use of a pair of cup washers, preferably made from a resilient material such as leather or the like, with these washers mounted on the valve stem so that they are adjacent each other and their cupped portions extend in opposite directions. At least one of these washers is capable of closing the drain hole when the hydrant valve is open and the washers are arranged so that their respective cupped portions are in the path of flow of water toward the drain hole both from the source of supply and from the hydrant standpipe.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of this device ready for use,

Fig. 2 is an enlarged cross-sectional view of Fig. 1 of this device showing the valve in closed position, with the dotted lines in the upper portion of the figure indicating the open position of the lever handle, and

Fig. 3 is an enlarged cross-section view of the valve assembly in Fig. 2 of this device but showing the valve in open position and showing the position of the double cup washer arrangement in respect to the drain hole.

Referring to the drawings I have used the numeral 10 to designate the standard water main

pipe through which water is pumped under pressure. The numeral 11 designates a valve seat body housing provided with the U-shaped channel 12 that communicates with the inlet and outlet portions of the housing, as shown in Fig. 3. The inside of the inlet and outlet portions of the housing 11 are threaded so that the inlet portion can be secured to the pipe 10 and the outlet portion can communicate with the standpipe 13. The numeral 14 designates a standpipe drain hole provided in the housing 11. Preferably I have threaded this drain hole so that a drain pipe can be secured thereto if desired. A nozzle is provided comprising the integrally formed portions, consisting of a jacket head chamber 15, the nozzle 16 that is threaded on its outside end portion, the water channel 17, a U-shaped open portion that has a bottom surface 18 in common with the top surface of the head chamber 15, as shown in Fig. 1 and Fig. 2, and two spaced apart horizontal bearing ears 19 above the U-shaped open portion to form the top of the nozzle head. The purpose of this open portion will be later described in detail.

The pipe 13 at its upper end communicates with the lower portion of the head chamber 15 and at its lower end with the housing 11, as heretofore described, thus forming a continuous water channel from the pipe 10 to the nozzle 16.

The numeral 20 designates a valve stem that is threaded at its upper end and arranged within the standpipe 13. The upper threaded end portion of this valve stem 20 slidably extends up through the head chamber 15 and protrudes above the surface 18 of the head chamber 15, as shown in Fig. 2. The numeral 21 designates a standard water-tight gland consisting of the gland packing and gland nut sleeve arranged within the head chamber 15. In Fig. 2 I show a connecting sleeve 22 because I preferably use a brass rod for the valve stem above the sleeve 22 while the portion below is of any suitably material. However, this is not necessarily required and the valve stem can be in one piece, if desired. My purpose in using the brass portion just described is not only for additional strength but because it will not rust, whereas many other types of tubing or pipe will rust and this in turn tends to tear the packing and thereby increase the possibility of leakage at this point. Also, if the valve stem is not formed from one piece of metal, the different portions may be the same size or different, and if different then an adapter sleeve must be used to join them together.

The lower end of the valve stem extends down into the housing 11, but not into chamber 12, and is operatively associated with the valve and plunger assembly which I will now describe. The numeral 23 designates a sleeve secured to the bottom of the valve stem, and the numeral 24 designates a cylindrical plunger threaded to the lower portion of the sleeve 23 and arranged within the housing 11, as shown in Fig. 3. The sleeve 23 and plunger 24 can be made in one piece as well as in two, as shown in my drawings, without affecting its function or efficiency. The numeral 25 designates an inwardly extending circumscribing lip formed in the lower inside end portion of the plunger and the numeral 26 designates a fillister head bolt slidably protruding from the bottom of the plunger 24 with the bolt head resting on the lip 25, as shown in Fig. 3. By this arrangement the bolt head is vertically slidable and rotatable within the chamber 27

5 of the plunger 24 and the bolt shank extends downwardly through the lower reduced portion 28 of the plunger and is likewise vertically slid-
able and rotatable therein.

10 The numerals 29 and 30 respectively designate a pair of cup washers and their arrangement in this device constitutes the novel feature of this invention.

15 Metal washers 31 and 32 are arranged on the bolt so that the upper one 31 engages the bottom of the reduced portion 28 of the plunger. While only one of the washers 31 and 32 is nec-
essary, I have illustrated the use of two merely to point out how more than one can be used to increase tension on the coil spring which I will later describe. The cup washer 29 is mounted on the bolt 26 with the cup portion up as shown in Fig. 3. The washer 30 is likewise mounted on the bolt and is adjacent the washer 29 but in-
verted in relation thereto so that its open portion extends downwardly as illustrated. A metal washer 34 is mounted on the bolt 26 and positioned within the confines of the cup washer 30. Each of these cup washers are of such a diameter as to frictionally slidably engage the inner wall 33 of the housing 11 and to also slidably frictionally engage the perimeter of the shank of bolt 26. The numeral 35 designates a flat retaining washer threaded to the end of the bolt 26 and the numeral 36 designates a coil spring arranged on the bolt 26 and having one end in communica-
20 tion with the washer 36 and its other end in communica-
tion with the bottom of the metal washer 34, as shown in Fig. 2 and Fig. 3. The numeral 37 designates a valve seat rubber washer detachably secured to the bottom of the bolt 26 by the stud screw 38.

25 The numeral 39 designates a lever handle member shaped substantially as shown in Fig. 2. The sides of the upper end portion of the handle 39 are flat and each of these sides are machined to form a stub shaft 40 that projects laterally therefrom. The numeral 41 designates a block bearing member that has a threaded hole through it, and a boss portion 42 formed on two opposite sides thereof. The numeral 43 designates two flat rectangular metal strap link members provided with holes in each respective end portions. The bearing member 41 is threaded to the top of the valve stem 20 where it protrudes above the surface 18. One end of one of the link members 43 is arranged on one of the boss mem-
30 bers 42 and the other end thereof is arranged on one of the stub shafts 40. The second link member 43 is similarly arranged on the oppo-
35 site side on the boss and stub shaft of the bearing member and handle respectively. The stub shaft portion of the handle is eccentrically ar-
40 ranged between the bearing ears 19 by means of the bolt and nut 44, as shown in Fig. 1 and Fig. 2. In this position the bearing ears 19 serve to keep the strap link member in place and no other securing means for this purpose is necessary.

45 My hydrant constructed and assembled as above described will operate in the following manner. The raising or lowering of the valve stem by means of the lever handle 39 will, of course, raise or lower the valve seat washer to control the flow of water under pressure from the pipe 10, as desired. As the handle is raised, it will, because of the eccentric, raise the strap link member 43 which in turn will raise the bearing member 41 that is threaded to the valve stem, thereby opening the valve. The handle will re-
50 main at any degree of open position desired

without any catches, springs, hooks or the like and the pressure of the water on the valve will not be able to open it any further because of the counter-balancing resistance offered by the handle due to the manner in which it is mounted.

The bearing member 41 provides a means for adjusting the valve seat washer when it is first installed and later if it should become unduly worn and compressed. In first installing the valve if it should be found that the valve seat washer does not fit tight enough, or later when the washer may have become worn, the bearing member can be rotated counterclockwise to lengthen the valve stem and likewise if the washer fits too tightly the bearing member can be rotated clockwise to shorten the valve stem. To thus have easy access to this bearing member I have positioned it above the head chamber 15 in the U-shaped open portion of the nozzle head above referred to.

It will be noted that when the valve is in closed position, as shown in Fig. 2, that the standpipe drain hole 14 in the housing 11 is not covered by the cup washer 29. However, the washer 29 will close this drain hole as it rises with the opening of the valve and as the valve is closed, this washer passes below the drain hole to permit the water in the standpipe to drain out. In this operation it should also be noted that before the cup washer 29 closes the drain hole in its upward movement it must of necessity travel the short distance to the hole and thus in present type hydrants if a slight opening of the valve is desired for a continuous slow flow, the drain hole will either be only partially closed or not closed at all because the valve seat washer moves in unison with the sleeve for covering the drain hole, thereby creating the disadvantages hereto mentioned.

In my device, however, the valve seat washer 37 and valve stem 20 do not always move in unison for, as I will point out, the washer 37 is stationary at times when the valve stem 20 may be moving either upwardly or downwardly. In Fig. 2, this hydrant is shown in closed position with the handle 39 down, the washer 37 is seated, the spring 36 is compressed and the washer 29 is below the drain hole 14. Also in closed position, the head of bolt 26 is in the upper portion of chamber 27. As the handle 39 is then raised, the valve stem 20, sleeve 23 and plunger 24 all being connected together, will rise accordingly as will the washers 29 and 30 which are held in tight engagement with the bottom of the plunger portion 28 as above described. The washers 29 and 30 move upwardly with the valve stem 20 since the raising of this stem releases pressure on the spring which urges the washers 29 and 30 upwardly. The effect of the spring is of course double acting so that in the initial upward movement of the valve stem 20 the washer 37 is held in seated position and remains there until the slack between the head of the bolt 26 and the lip 25 is taken up. This slack is sufficient for the washer 29 to completely close the drain hole 14 before the lip 25 engages the bolt 26 at which time the washer 37 will then rise in unison with movement of the valve stem 20. Thus, it will be observed that the washer 37 may be unseated to obtain any desired flow and maintained thereat without permitting leakage at the drain hole which is closed prior to the unseating of the washer 37.

When closing this hydrant, the washers 31,

29, and 30 and plunger 24 will move initially in unison because the plunger portion 28 engages the washers 31 and 32 that transmit force through washers 29 and 30, through washer 34 to the spring 36 which compresses as it seats washer 37. The washer 37 will seat before the handle 39 is fully lowered and as the handle is continued downwardly, the spring 36 is further compressed and the plunger moves downwardly on the shank 10 of bolt 28 to create slack between the head of the bolt and lip 25 in chamber 27 as above described. The washers 29 and 30 move downwardly with the plunger and open the drain hole 14 when the handle 39 is fully lowered.

15 It will also be observed that this spring being compressed when the valve is closed is constantly exerting a downwardly pressure on the valve seat washer. Consequently, if the valve seat washer begins to wear, the tension in the coil 20 spring will automatically tend to maintain it tightly in the valve seat and compensate for wear, thereby prolonging the useful life of the washer and more important, providing an additional safeguard against preventing leakage and 25 the resulting waste of valuable water. Should the valve seat washer become worn to a degree greater than the coil spring can compensate for, then an additional manual adjustment can be made by the bearing member at the top of the 30 valve stem as previously described.

It will also be observed that when the lever handle is moved to close the valve, this spring absorbs some of the pressure therefrom so that the valve seat rubber washer 37 is eased onto 35 the valve seat and cannot be jammed into closed position. This effect considerably prolongs the life of the washer 37.

Once in its open position this hydrant may 40 be left in that position indefinitely without danger of losing water through the drain hole and this is due to the arrangement of the two cup washers 29 and 30. With a continuous flow of water through the housing 11 from the pipe 10, the bulk of the water will of course flow 45 through the channel 12 into the standpipe. However, there is obviously water pressure against the bottom of the valve and around the plunger 24 and it is at these points where the pressure eventually forces water to the drain 50 hole in most current type hydrants. In my device, however, the inverted cup washer 30 forms a tight seal against the inner wall 33 below the drain hole 14 and water under pressure from 55 below merely fills this cup washer and thereby further increases the frictional contact thereof against the wall 33 to prevent any leakage through the hole 14. The cup washer 29 will in a similar manner seal off the drain hole from 60 above. It will also be observed that due to the manner of mounting the washers 29 and 30 on the shank of bolt 26 as above described, that there is no leakage of water intermediate the bolt shank and these washers so that all flow 65 of water to the nozzle must pass through channel 12.

Thus, in my device the cupped portion of the 70 respective washers will be in the path of flow of water toward the drain hole both below and above it. Obviously, the more pressure exerted against the interior of the cup washers, the tighter will be the seal against the wall 33. This insures against water passing through the drain hole until the valve is closed and the washers moved away from the drain hole.

The handle on my invention is shaped so that it can be easily grasped by hand and because of its position relative to the nozzle head, its open or closed position can be ascertained merely by visual observation. This is of great advantage at times to the farmer who may wish to look across his barn or yard area to see whether his hydrant is on or off. I also wish to point out that due to the swivel arrangement of the bolt 26 within the plunger 24, there is no twisting of the washer 37 on its valve seat when the hydrant head is removed for repairs or inspection. Obviously if the head is rotated to remove it from the standpipe and withdraw the valve stem 20 and valve assembly, the stem 20 and plunger will rotate. Normally, the washer 37 would likewise rotate and thus cause undue wear thereon. However, in my arrangement, the washer 37 being secured to the bolt 26 remains stationary even though the plunger rotates and thus is a safeguard for prolonging the useful life thereof.

Some changes may be made in the construction and arrangement of my hydrant without departing from the real spirit and purpose of my invention, and it is my intention to cover by my claims, any modified forms of structure or use of mechanical equivalents which may be reasonably included within their scope.

I claim:

1. In combination with a valve housing having an inlet and an outlet connected by a C-shaped channel and a side drain hole oppositely disposed from said channel and communicating only with said outlet, a valve assembly, comprising, a valve stem slidably disposed in said housing in the same plane as a direct line between said inlet and outlet, means for moving the same in two vertical directions respectively, a cylindrical plunger secured to the bottom of said valve stem, an internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a first disc washer on said bolt within the confines of the upper cupped washer, a second disc washer on said bolt within the confines of said lower cupped washer, a third washer on the bottom of said bolt adapted to seat at times in said inlet, a yielding means on said bolt having one end engaging said second disc washer and the other end engaging said third washer, each of said cupped washers blocking the flow of water therewith from one direction respectively, said yielding means compressed by said plunger, said bolt head portion out of engagement with said shoulder, said third washer seated and said drain hole open when said valve stem is in its lowermost position, and when said valve stem is being moved towards its uppermost position, said bolt initially remaining stationary under tension of the expanding yielding member to hold said third washer seated while said cupped washers move upwardly on said bolt shank under pressure of said expanding yielding means so that at least the upper cupped washer closes said drain hole and after which said shoulder engages said bolt head portion to move the same upwardly in unison with said valve stem and unseat said third washer.

with said valve stem and unseat said third washer.

2. A device as defined in claim 1 in which when said valve stem is being moved from its uppermost to lowermost position, said bolt initially moves downwardly therewith under contact of said plunger on said first disc washer until said third washer is seated and thereupon remains stationary while said plunger continues to move downwardly to compress said yielding means and move said cupped washers past said drain hole to open the same.

3. In combination with a valve housing having an inlet and an outlet connected by a C-shaped channel and a side drain hole oppositely disposed from said channel and communicating only with said outlet, a valve assembly, comprising, a valve stem slidably disposed in said housing in the same plane as a direct line between said inlet and outlet, means for moving the same in two vertical directions respectively, a cylindrical plunger secured to the bottom of said valve stem, an internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a third washer on the bottom of said bolt adapted to seat at times in said inlet, a yielding means on said bolt having one end engaging one of said cupped washers and the other end engaging said third washer, each of said cupped washers blocking the flow of water therewith from one direction respectively, said yielding means compressed by said plunger, said bolt head portion out of engagement with said shoulder, said third washer seated and said drain hole open when said valve stem is in its lowermost position, and when said valve stem is being moved towards its uppermost position, said bolt initially remaining stationary under tension of the expanding yielding member to hold said third washer seated while said cupped washers move upwardly on said bolt shank under pressure of said expanding yielding means so that at least the upper cupped washer closes said drain hole and after which said shoulder engages said bolt head portion to move the same upwardly in unison with said valve stem and unseat said third washer.

4. In combination with a valve housing having an inlet and an outlet connected by a water channel and having a side drain hole communicating only with said outlet, a valve assembly, comprising, a valve stem slidably disposed in said housing, means for moving the same in two vertical directions respectively, a cylindrical plunger secured to the bottom of said valve stem, an internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a first disc washer on said bolt within the confines of the upper cupped washer, a second disc washer on said bolt within the confines of said lower cupped washer, a third washer on the bottom of said bolt.

of said bolt adapted to seat at times in said inlet, a yielding means on said bolt having one end engaging said second disc washer and the other end engaging said third washer, each of said cupped washers blocking the flow of water therewith from one direction respectively, said yielding means compressed by said plunger, said bolt head portion out of engagement with said shoulder, said third washer seated and said drain hole open when said valve stem is in its lowermost position, and when said valve stem is being moved towards its uppermost position, said bolt initially remaining stationary under tension of the expanding yielding member to hold said third washer seated while said cupped washers move upwardly on said bolt shank under pressure of said expanding yielding means so that at least the upper cupped washer closes said drain hole and after which said shoulder engages said bolt head portion to move the same upwardly in unison with said valve stem and unseat said third washer.

5. In combination with a valve housing having an inlet and an outlet connected by a water channel and having a side drain hole communicating only with said outlet, a valve assembly, comprising, a valve stem slidably disposed in said housing, means for moving the same in two vertical directions respectively, a cylindrical plunger secured to the bottom of said valve stem, an internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a third washer on the bottom of said bolt adapted to seat at times in said inlet, a yielding means on said bolt having one end engaging one of said cupped washers and the other end engaging said third washer, each of said cupped washers blocking the flow of water therewith from one direction respectively, said yielding means compressed by said plunger, said bolt head portion out of engagement with said shoulder, said third washer seated and said drain hole open when said valve stem is in its lowermost position, and when said valve stem is being moved toward its uppermost position, said bolt initially remaining stationary under tension of the expanding yielding member to hold said third washer seated while said cupped washers move upwardly on said bolt shank under pressure of said expanding yielding means so that at least the upper cupped washer closes said drain hole and after which said shoulder engages said bolt head portion to move the same upwardly in unison with said valve stem and unseat said third washer.

6. In a hydrant of the class described, a housing having an inlet and an outlet, a drain hole intermediate said inlet and outlet at one side of said housing, an unobstructed water channel connecting said inlet and outlet on the other side of said housing, a valve assembly operable in said housing intermediate said water channel and drain hole, said valve assembly comprising, a valve stem mounted to slide in said housing in the direction of its length, a cylindrical plunger secured to the bottom of said valve stem, an

internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a first disc washer on said bolt within the confines of the upper cupped washer, a second disc washer on said bolt within the confines of said lower cupped washer, a third washer on the bottom of said bolt adapted to seat at times in said inlet, a yielding means on said bolt having one end engaging said second disc washer and the other end engaging said third washer, each of said cupped washers blocking the flow of water therewith from one direction respectively, said bolt movable upwardly and downwardly at times in unison with said valve stem and being stationary at times during the movement of said valve stem, movement of said cupped washers always being in unison with said valve stem, and one of said cupped washers operating to open and close said drain hole.

7. In a hydrant of the class described, a housing having an inlet and an outlet, a drain hole intermediate said inlet and outlet at one side of said housing, an unobstructed water channel connecting said inlet and outlet on the other side of said housing, a valve assembly operable in said housing intermediate said water channel and drain hole, said valve assembly comprising a valve stem mounted to slide in said housing in the direction of its length, a cylindrical plunger secured to the bottom of said valve stem, an internal shoulder in said plunger, a bolt having its head portion slidable and rotatable within said plunger intermediate said shoulder and the bottom of said valve stem, said bolt head portion engageable with said shoulder, a pair of cupped washers frictionally slidably arranged on the shank portion of said bolt, said washers being adjacent each other and having their cupped portions extending in opposite directions, a third washer on the bottom of said bolt adapted to seat at times in said inlet, a yielding means on said bolt having one end engaging one of said cupped washers and the other end engaging said third washer, each of said cupped washers blocking the flow of water therewith from one direction respectively, said bolt movable upwardly and downwardly at times in unison with said valve stem and being stationary at times during the movement of said valve stem, movement of said cupped washers always being in unison with said valve stem, and one of said cupped washers operating to open and close said drain hole.
